UNITED STATES PATENT OFFICE.

FREDRICK S. DICKINSON, OF NEW YORK, N. Y.

DESIGN FOR A VEHICLE TIRE.

Application filed July 7, 1922. Serial No. 2,982. Term of patent 3½ years.

To all whom it may concern:

Be it known that I, FREDRICK S. DICKINSON, residing at New York, county and State of New York, have invented a certain new, original, and ornamental Design for a Vehicle Tire, of which the following is a specification, reference being had to the accompanying drawing, forming part thereof.

Figure 1 is a top plan view; and

Figure 2 is a cross-sectional view of the tread.

I claim:

The ornamental design for a vehicle tire.

FREDRICK S. DICKINSON.

Witnesses:

CHARLES H. O'CONNOR,
FREDERICK GUNTHNER.
